UNITED STATES PATENT OFFICE.

ARTHUR Q. GENTRY AND JASPER A. BURK, OF MILBURN, TEXAS.

ATTACHMENT FOR HORSE-POWERS.

SPECIFICATION forming part of Letters Patent No. 761,160, dated May 31, 1904.

Application filed May 11, 1903. Serial No. 165,161. (No model.)

To all whom it may concern:

Be it known that we, ARTHUR Q. GENTRY and JASPER A. BURK, citizens of the United States, residing at Milburn, in the county of McCulloch and State of Texas, have invented a new and useful Attachment for Horse-Powers and the Like, of which the following is a specification.

This invention relates to attachments for the power-transmission apparatus employed more particularly in connection with hay-preserves and similar devices, and has for its object to provide means whereby the movement is retarded at a certain predetermined portion of the movements to prevent the rebound of the stroke from being communicated to the horses when horses are employed as a motive power or to the parts of any power of whatsoever kind employed.

The device is more particularly applicable to horse-power apparatus to prevent injury to the animals during the operation of the pressing machinery, but may be employed to advantage in connection with other forms of machinery, and we do not, therefore, desire to be limited in the use of the device to any specific structure or to machinery driven by any specific motive power, but reserve the right to its use wherever applicable.

In the drawings illustrative of the invention, in which corresponding parts are denoted by like designating characters, Figure 1 is a longitudinal sectional elevation. Fig. 2 is a rear elevation of a portion of a power-transmitting apparatus with the improvement applied. Fig. 3 is an inverted plan view illustrating the operation of the improved device. Fig. 4 is an enlarged perspective view of the improved check-spring detached.

For the purpose of illustration the device is shown applied to an improved structure adapted to be operated by horse-power, in which—

10 represents a portion of the press-box, 11 the plunger, and 12 the connecting or operating bar or beam movably connected at one end to the plunger in the usual manner. Extending from the press-box are spaced base or string timbers 13 14, connected near their outer ends by a transverse sill 15, having ex-

tended ends, as shown. Rising from the sill member are spaced vertical members 16 17, connected at their upper ends by a "header," preferably formed in two parts 18 19, "halved" upon the vertical members and connected thereto and also to each other between the vertical members by transverse bolts 20, as shown. At their lower ends the vertical members 16 17 are connected by a foot member, preferably formed in two parts 21 22 and secured, like the header member, by transverse bolts 23, as shown. Between the head and foot members is secured an intermediate member, preferably in two portions 24 25 and secured by transverse bolts 26, similarly to the foot and head members, as shown. The vertical members 16 17 will be further supported by diagonal braces 38 39, as shown. The intermediate member 24 25 is nearer the header member than to the lower or base member 21 22, and mounted for rotation between these parts is a vertical drive-shaft 27, journaled, as shown, between the coupled members and extended at the upper end to provide for the reception of the sweep 28 or other power-applying means. The shaft 27 also carries a gear-pinion 29 between the header and intermediate members, as shown.

Journaled vertically in the header, base, and intermediate members is a shaft 30, having a crank 31 between the base and intermediate members and a gear-wheel 32 between the header and intermediate member, intermeshing with the pinion 29, as shown. The connecting-bar 12 is coupled by its outer end to the crank 31, as shown, and it will thus be obvious that power applied to the shaft 27 will cause the plunger 11 to be actuated in the press-box.

In apparatus of this character at the moment of the release of the plunger at the beginning of the return stroke a rebound motion is imparted to the connecting-bar and its connected parts, caused by the sudden withdrawal of the pressure from the plunger, and this rebound frequently results in throwing the sweep against the horses, as well as producing violent jars and concussions in the other parts of the machinery. To check this rebound and prevent its transmission to the

sweep or other parts, a check-spring 33 is arranged in the path of the crank at its return stroke, and in engagement with which the crank moves during the "rebound" period of its stroke, the spring thus absorbing the jars and concussions incident thereto and effectually preventing their transmission to the sweep or other parts. The spring may be arranged above or below the crank and will 10 preferably be so disposed that one of the side arms of the crank engages it, as shown. The check-spring member is shown formed of a resilient central portion with lateral threaded ends 34 35, secured in place by nuts, as shown, 15 and of proper length to maintain a resisting strain upon the crank for a length of time sufficient to accomplish the desired results. By this simple means the heretofore annoying and dangerous rebound action of the plunger and connecting-bar is efficiently resisted and all the jars and concussions absorbed and 20

prevented from being communicated to the sweep or other connected parts.

Having thus described our invention, what we claim, and desire to secure by Letters Patent, is—

In an apparatus of the class described, a supporting-frame, a shaft having a crank and mounted for rotation in said frame, and an approximately U-shaped resilient member 30 with its legs secured to said frame and the convex surface of the base thereof disposed in the path of said crank to be intermittently engaged thereby.

In testimony that we claim the foregoing as 35 our own we have hereto affixed our signatures in the presence of two witnesses.

ARTHUR Q. GENTRY.

JASPER A. BURK.
